UNITED STATES PATENT OFFICE.

MARVIN D. BENNETT, OF SIDNEY, NEW YORK.

ANCHORING DEVICE FOR RAILROAD-ROLLING-STOCK BUMPERS.

1,300,108.

Specification of Letters Patent.

Patented Apr. 8, 1919.

Application filed January 7, 1919. Serial No. 270,024.

To all whom it may concern:

Be it known that I, MARVIN D. BENNETT, a citizen of the United States, residing at Sidney, in the county of Delaware and State of New York, have invented certain new and useful Improvements in Anchoring Devices for Railroad-Rolling-Stock Bumpers, of which the following is a specification.

This invention relates to improvements in anchoring means for use in securing railroad rolling stock bumpers to the tracks or adjacent the tracks in a manner such as will materially add to the durability and practicability of a bumper secured therewith; preventing distortion or fracture of the bumper or parts of the bumper and also, preventing distortion of the rails of a railroad track, should the bumper be connected thereto, as is often the case.

Another and equally important object of the invention is to provide a form of anchoring means which will successfully withstand and render harmless impacts of considerable force by evenly diffusing the stress incurred thereby throughout the structure of the device.

Other objects will be in part obvious and in part pointed out hereinafter.

In order that the invention and the manner of its application may be readily understood by those skilled in the art, I have in the accompanying illustrative drawings and in the detailed following description based thereon set forth a preferred embodiment of the invention.

In these drawings:

Figure 1 is a top plan view of the anchoring means as applied to the rails of a railroad track; and

Fig. 2 is a vertical transverse section therethrough, slightly enlarged.

Having more particular reference to the drawings, in connection with which like reference characters will designate corresponding parts throughout the several views, *r* represents the spaced rails of a railroad track, the same being arranged on longitudinally disposed stringers 1, which stringers as will be understood are arranged on a suitable ballast or bed, common in this art.

Spanning the spaced rails *r* is a transversely disposed tie 2, secured at its opposite ends to adjacent portions of the longitudinal stringers 1 passing bolts 3 or similar connecting devices therethrough. This transverse tie 2 serves to receive the rolling

stock bumper designated in its entirety by the numeral 4 thereon, the bumper of course being provided with a suitable form of stand or other support which is in turn connected to the adjacent portions of the tie 2 by bolts or similar fastening devices.

A second tie 5 is provided and is arranged forwardly of and in spaced relation to the tie 2, the same spanning the rails *r* and being arranged in parallelism to the tie 2. Bolts or their equivalents 6 may be and preferably are passed through the opposite end portions of the tie 5 into engagement with adjacent portions of the longitudinal stringers 1 thus effecting positive connection between these three elements. It however, will be noted in this connection, that instead of being arranged over the stringers 1, as is the case with the tie 2, the tie 5 is arranged adjacent the under sides of the stringers 1 and by consequence, affords a desirable form of bracing means capable of connection with the bumper 4 arranged on the tie 2; it of course being understood that the impacts upon the bumper 4 will have the stress incurred thereby transmitted in part to the tie 5 and from where such part of the stress will be evenly diffused through the tie 5 and the stringers 1 in a manner to prevent distortion of the rails *r* or distortion or other injury to the tie 5 and the stringers 1.

Passing vertically through the adjacent portions of the tie 5 and the stringers 1 are the offset end portions of bracing connections 7, the free ends of the offset end portions of these connections being screw-threaded and receiving suitable forms of bearing plates 8 thereover, whereupon nuts 9 or their equivalents are turned into engagement with said screwthreaded ends. The braces 7 extend substantially upward into engagement with the bumper proper through any suitable form of connection. For the purpose of convenience, however, I have shown these connections as being passed through diagonally disposed apertured lugs generally carried on the sides of the bumper housing. In this connection, although, it will be borne in mind that the particular form of anchoring means is not limited for use upon any one particular design or make of bumper, but in fact, may be used on all types of bumpers constructed along these lines, such as conditions or preference may dictate. Obviously, by rea-

son of the connection of the bumper proper with the forwardly disposed tie 5 through the medium of the connections 7, a very desirable and effectual form of bracing means 5 will be provided; a bracing means which will prevent distortion or other injury to the active parts of the device as well as to the rails *r* such as might be caused by upward pulls resulting from the stress incurred by 10 impacts of rolling stock with the bumper, the active elements of the anchoring means being so positioned with relation to each other as to effectually brace the construction throughout and cause the even diffusion 15 of stress therethrough. The connection of the stand or support of the bumper 4 with the tie 2 is also such as will serve to prevent undue movement of the stringers.

Manifestly, the construction shown is capable 20 of considerable modification and such modification as is within the scope of my claims, I consider within the spirit of my invention.

I claim:

25 1. A bumper anchoring means including in combination with the rails of a track, a longitudinally disposed base means arranged under portions of said rails, a transverse tie spanning the rails and connected at its op-

posite end portions to portions of the base 30 means and positioned adjacent the upper sides of the base means, said tie serving to receive the bumper thereon, a second transverse tie spanning the rails and arranged adjacent the lower faces of the base means and 35 connected to said base means, and bracing connections extending from said last mentioned tie upwardly into engagement with the bumper.

2. A bumper anchoring means comprising 40 in combination with the rails of a track, longitudinal stringers arranged under portions of said rails, a transverse tie spanning the rails and arranged adjacent the upper sides of the ties and connected thereto, said 45 tie receiving the bumper thereon, and a second tie disposed transversely of the rails and arranged adjacent the lower faces of said stringers and connected thereto, said second tie being arranged forwardly of the 50 first tie, and bracing rods engaged at their lower ends with the forwardly disposed tie and extending diagonally upward into engagement with the bumper.

In testimony whereof, I affix my signature hereto.

MARVIN D. BENNETT.
